US00D704712S

(12) **United States Design Patent**
Sugino et al.

(10) **Patent No.:** **US D704,712 S**
(45) **Date of Patent:** **** May 13, 2014**

(54) **HOUSING COMPONENT FOR ELECTRONIC COMPUTER**

(71) Applicant: **Nintendo Co., Ltd.**, Kyoto (JP)

(72) Inventors: **Kenichi Sugino**, Kyoto (JP); **Yui Ehara**, Kyoto (JP); **Takaki Fujino**, Kyoto (JP); **Junichiro Miyatake**, Kyoto (JP); **Tetsuya Akama**, Kyoto (JP); **Hironori Akai**, Kyoto (JP); **Kochi Kawai**, Kyoto (JP); **Kumpei Fujita**, Kyoto (JP)

(73) Assignee: **Nintendo Co., Ltd.**, Kyoto (JP)

(**) Term: **14 Years**

(21) Appl. No.: **29/439,983**

(22) Filed: **Dec. 18, 2012**

(30) **Foreign Application Priority Data**

Jun. 18, 2012 (JP) 2012-014502

(57) **CLAIM**

The ornamental design for a housing component for electronic computer, as shown and described.

DESCRIPTION

FIG. 1 is front, right and bottom perspective view of a housing component for electronic computer showing our new design; FIG. 2 is rear, left and top perspective view thereof; FIG. 3 is a front view thereof; FIG. 4 is a rear view thereof; FIG. 5 is a top plan view thereof; FIG. 6 is a bottom plan view thereof; FIG. 7 is a left side view thereof; and, FIG. 8 is a right side view thereof.
